Patented Dec. 15, 1925.

UNITED STATES PATENT OFFICE.

JOHN M. B. LEWIS, OF LYNCHBURG, VIRGINIA.

HEADLIGHT.

Application filed November 3, 1922. Serial No. 598,793.

To all whom it may concern:

Be it known that I, JOHN M. B. LEWIS, a citizen of the United States, residing at Lynchburg, in the county of Campbell and State of Virginia, have invented certain new and useful Improvements in Headlights, of which the following is a specification.

This invention relates to headlights and more particularly to headlights for automobiles wherein the direct rays of light are prevented from being thrown into the eyes of drivers of automobiles approaching in the opposite direction.

As is well known numerous attempts have been made to provide non-glare headlights for automobiles, the usual method being to provide lenses having surfaces of peculiar configuration whereby the rays of light are thrown downwardly. These devices have not been wholly satisfactory since a certain amount of the direct rays of light are thrown in the eyes of drivers of approaching vehicles.

It is an important object of the present invention to provide a headlight structure employing a lighting unit and a reflector both of which are screened from the view of a driver of a vehicle approaching in the opposite direction.

Other objects and advantages of the invention will be apparent during the course of the following description.

In the drawings I have shown one embodiment of the invention. In this showing, Figure 1 is a central vertical longitudinal sectional view, and,

Figure 2 is a front elevation.

Referring to the drawings the numeral 10 designates, as a whole, a preferably sheet metal lamp casing having a substantially horizontal central upper portion 11, the metal of the lamp curving upwardly as at 12 toward the front end thereof and terminating in the relatively short horizontal portion 13. As shown in Figure 2 the forward end of the casing is substantially rectangular and the lower portion 14 of the lamp slopes downwardly and rearwardly to a curved and enlarged rear portion 15. The casing is adapted to be supported in a bracket 16, being adjustably secured thereto by bolts 17.

The forward open end of the casing is closed by a door 18 having the usual glass or lens 19 arranged therein as shown. The door 18 has a relatively narrow rectangular opening 20 therein. The door 18 is hinged

at its upper end to the casing 10 as at 21, while the lower end thereof is secured to the casing by a nut 22 carried by a stem 23 and adapted to engage within forks 24 carried by the lower wall 14 of the casing.

The curved portion 15 of the casing is provided with a slot 25 in which is mounted the stem 26 of an electric bulb or other lighting unit 27. A parabolic reflector 28 is rigidly secured to the stem 26 and the latter, as shown, projects outwardly of the casing through the slot 25. The outer portion of the stem 26 is secured to a rod 29, the outer end of which is threaded as at 30. A bracket 31 is secured to the rear portion of the casing 10 above the stem 26 of the lighting unit, and is provided with an opening in which the rod 29 is loosely mounted. Locks nuts 32 are threaded upon the rod 29 upon opposite sides of the bracket 31 whereby the position of the lighting unit and its parabolic reflector may be adjusted.

A reflector 33 is arranged in the upper portion of the casing as shown in Figure 1, the forward portion of the reflector curving upwardly as at 34 and terminating at a point spaced from the forward end of the casing. The numeral 35 designates a light screen arranged in the upper forward portion of the casing, the screen being hinged to the casing as at 36. A threaded arcuate rod 37 is connected to the forward end of the screen 35 by an eyelet 38 and projects upwardly through an opening in the portion 13 of the casing, a nut 39 being threaded upon the upper end of the rod 37.

It will be seen in Figure 1 that the lower and rear end of the reflector 33 is arranged at a point slightly above the upper line of the opening 20 as indicated by the dotted line therethrough. The lighting element 27 and parabolic reflector 28 are arranged at a position wholly below the lower line of the opening 20 as indicated by the dotted line 100 above the upper end of the reflector 28. It will be apparent that drivers of vehicles approaching in the opposite direction are protected from the direct rays of light from the light 27 and reflectors 28 and 33 by virtue of their arrangement with respect to the opening 20 in the cover 18, the paths of the rays of light being indicated by the dot and dash line in Figure 1. The mounting of the stem of the light permits adjustment of the latter whereby the paths of the rays of light may be varied somewhat to

throw the rays of light closer to or further from the vehicle upon which the device is mounted. The screen 35 may be adjusted if necessary to intercept any rays of light passing upwardly at an angle through the upper portion of the opening 20, the screen 35 also serving as a reflector to reflect rays of light downwardly upon the forward portion of the machine and the ground adjacent the forward portion of the machine.

It is to be understood that the form of my invention herewith shown and described is to be taken as a preferred example of the same and that various changes in the shape, size, and arrangement of parts may be resorted to without departing from the spirit of the invention or the scope of the subjoined claims.

Having described my invention, I claim:

20. 1. A device of the character described comprising a casing having an opening in its forward end, an approximately horizontally arranged reflector disposed in the upper portion of said casing wholly above the upper line of said opening, the forward portion of said reflector being curved upwardly, and a lighting unit arranged in the lower portion of said casing rearwardly of said reflector and wholly below the lower line of said opening.

25. 2. A device of the character described comprising a casing having an opening in its forward end, an approximately hori-

zontally arranged reflector disposed in the upper portion of said casing above the upper line of said opening, the forward portion of said reflector being curved upwardly, a lighting unit arranged in the lower portion of said casing rearwardly of said reflector and below the lower line of said opening, and a vertically movable screen arranged between said reflector and the upper portion of the opening in said casing the lower edge of said screen being adapted to be arranged wholly below the level of the lowermost portion of said reflector.

3. A device of the character described comprising a casing having an opening in its forward end, an approximately horizontally arranged reflector disposed in the upper and forward portion of said casing above the upper line of said opening, said reflector having its forward portion curved upwardly and terminating at a point spaced from the forward end of said casing, a screen pivotally connected at its upper end adjacent the forward end of said reflector, the lower edge of said screen being adapted to be arranged below the level of the lowermost portion of said reflector, means for adjusting said screen, and a lighting unit arranged in the lower rear portion of said casing wholly below the lower line of the opening therein.

In testimony whereof, I affix my signature.
JOHN M. B. LEWIS.
